US00D903864S

(12) **United States Design Patent** (10) **Patent No.:** **US D903,864 S**
Fabrikant et al. (45) **Date of Patent:** **** Dec. 1, 2020**

(54) **MEDICATION MIXING APPARATUS**

(71) Applicant: **West Pharma. Services IL, Ltd.**, Ra'anana (IL)
(72) Inventors: **Elisheva Fabrikant**, Herzliya (IL); **Raymond Protasiewicz**, Whippany, NJ (US); **Brian Costello**, Whitehouse Station, NJ (US)

(73) Assignee: **WEST PHARMA. SERVICES IL, LTD.**, Ra'anana (IL)

(**) Term: **15 Years**

(21) Appl. No.: **29/674,063**

(22) Filed: **Dec. 19, 2018**

(30) **Foreign Application Priority Data**

Jun. 20, 2018 (IL) D62256
Jun. 20, 2018 (IL) D62258

(51) **LOC (12) Cl.** **24-02**

(52) **U.S. Cl.**

USPC **D24/129**

(57) **CLAIM**

The ornamental design for a medication mixing apparatus, as shown and described.

DESCRIPTION

FIG. 1 is a front perspective view of a medication mixing apparatus in accordance with our new design;

FIG. 2 is a left side elevational view of FIG. 1;

FIG. 3 is a right side elevational view of FIG. 1;

FIG. 4 is a front elevational view of FIG. 1;

FIG. 5 is a rear elevational view of FIG. 1;

FIG. 6 is a top plan view of FIG. 1; and,

FIG. 7 is a bottom plan view of FIG. 1.

The broken lines show portions of the design that form no part of the claimed design.

1 Claim, 6 Drawing Sheets
